(57) **CLAIM**

The ornamental design for a red dot sight, as shown and described.

DESCRIPTION

FIG. 1 is a front view of a red dot sight, showing our new design;

FIG. 2 is a back view of the red dot sight;

FIG. 3 is a left view of the red dot sight;

FIG. 4 is a right view of the red dot sight;

FIG. 5 is a top view of the red dot sight;

FIG. 6 is a bottom view of the red dot sight;

FIG. 7 is a perspective view of the red dot sight; and,

FIG. 8 is another perspective view of the red dot sight.

The broken lines in the drawings disclose the unclaimed portions of the red dot sight only and form no part of the claimed design.
